UNITED STATES PATENT OFFICE

2,446,487

HOOD AND FENDER JIG

John Franklin O'Kelley, Dallas, Tex.

Application March 16, 1945, Serial No. 583,075

2 Claims. (Cl. 153—51)

1

This present invention relates to a device for restoring the original shape of hoods and/or fenders of automobiles or trucks or parts of other vehicles that have had these parts deformed in a collision or otherwise.

This so-called jig can be placed on the floor of an automotive repair shop and comprises pairs of coating screw or hydraulic jacks engaging the deformed part of a hood or fender and restoring its original shape. The position of the jacks is adjustable.

On the front side of the apparatus and on either side thereof are fastened two adjustable arms intended to support the automobile or other vehicle part to be restored to its original shape.

It will be understood that the construction of the present invention lends itself readily to other uses including, for example, pressing out cross-head pins in the installation of new bearings in a vehicle part, and during the overhauling of a front end assembly the spindle bearings, wrist pins or the like can be pressed out.

Instead of wooden frame material as shown herein, the parts appropriate thereto can be made of channel or angle iron.

To the foregoing objects and others which may hereinafter appear, the invention consists of the novel construction, combination and arrangement of parts as will be more specifically referred to and illustrated in the accompanying drawings, but it is to be understood that changes, variations and modifications may be resorted to which fall within the scope of the invention as claimed.

In the drawings:

Figure 1 is a perspective view of the preferred embodiment of my invention.

Figure 2 is a vertical section taken on the line 2—2 of Figure 3.

Figure 3 is a vertical transverse section taken on the line 3—3 of Figure 1.

Figure 4 is a vertical transverse section of a modified form of my invention.

Figure 5 is a fragmentary view taken on the line 5—5 of Figure 3.

In Figure 1, numerals 2 denote base pieces of wood or metal, or other suitable material of sufficient length to give the apparatus the required stability. Vertical columns 3 are attached to the inner sides and approximately at the center of the base pieces 2. To insure a rigid connection between the parts mentioned, inclined braces 4 are secured by screws, bolts, or other fastening means 5 at their lower end to the inner side of pieces 2 and at their upper ends by fastening

2

means 6 to the columns 3. The latter are each provided with a pair of series of equidistant holes 7 extending parallelly and adjacent to the narrower edges of the columns 3. These are connected by two sets of cross beams 8, each set consisting of a pair of parallel beams. In order to support a set between the columns 3, angle irons 9 are attached to the upper and lower narrow edge and near the ends of a beam by screws or otherwise. Bolts 10 pass through holes in the vertical legs 11 of the angles 9 and selected holes 7 in columns 3.

Notches in the upper and lower narrow edges of beams 8 provide seats for cross bars 12 and are of such depth as to cause the top or bottom surface of the latter to be flush with the top or bottom surface of the narrow edge of the beams 8. Screws 13 pass through the cross bars 12 and are threaded into the beams 8.

20 The upper cross bars 12 have central threaded apertures for the reduced and exterior threaded portions 14 of flanged nuts 16 which carry lock nuts 17 upon their threaded lower ends projecting beneath the cross-bars 12.

25 The lower cross bars 12 of each beam are centrally apertured and function as guides for the screws 18 which are threaded through the nuts 16. The screws 18 in cross bars 12 of the upper beam 8 have handles 19 at their upper ends and 30 fender or hood engaging members 20 at their lower ends. The screws 18 of the lower beam 8 have members 20 at their upper ends and handles 19 at their lower ends. The members 20 have convex surfaces 22 facing the hood or fender to

35 be operated upon and these surfaces are covered with a suitable material 23 such as leather or rubber which is held on the member 20 by wires 24 or otherwise. The connection between a member 20 and its screw 18 is such as to permit 40 relative rotation. The end portion of each screw 18 is peripherally grooved at 25 and is received in a socket 26 of a member 20 and held therein by a pin 27 lying in a portion of the groove 25 and passing through the socketed portion of the

45 member 20. This connection between the screw 18 and its work engaging member 20 makes it possible to place the latter in a position in which its curvature is that which the hood or fender portion in engagement therewith originally possessed and which is to be restored.

In order to hold a fender or hood to be operated on in the proper position arms 28 are provided each consisting of a lower inner section 29 and upper outer section 30 telescoped over the former. Section 29 is connected by a knuckle joint to one

of the base pieces 2. The knuckle joint comprises a ball portion 31 constituting the lowermost end of section 29 and a plate 32 affixed to base 2 having an aperture large enough for the section to describe a conical surface, but too small for the ball 31 to pass through.

A set screw 33 is threaded into the upper section 30 and engages the inner section 29 with its inner end. Thus the length of the arm 28 may be adjusted to suit the requirements of a bending or straightening operation. In order to permit a further adjustment of the arms 28, each upper section 30 is made in two portions 34, 35 flattened at the apertured coaching ends and held in a desired angular relation by a screw bolt 36 with a wingnut 37. The top portion 35 of section 30 is longitudinally slotted (38) at its upper end to receive a part of the work which is held in the slot by a set screw 39, threaded into one of the legs of slot by a wing head.

Figure 4 illustrates a modification in which hydraulic or pneumatic jacks are used and which dispenses with the upper cross bars of the upper beam and the lower cross bars of the lower beams. Thus the jacks engaging the top surface of the work are suspended from the lower cross bars of the upper beams and the jacks engaging the bottom surface of the work are secured on the upper bars of the lower beam. In other respects the modification of Figure 4 conforms to the preferred embodiment illustrated by Figures 1-3.

Each fluid jack used in the embodiment of Figure 4, comprises a base 40 attached by bolts 41 or other fastening means to a cross bar 12 as outlined above, a housing 42 carried by the base 40 and including a pump structure, and two telescopically related pistons 43, 44 slideable in the housing 42. The pump structure consists of a fulcrum link 45 pivoted at one end to the housing 42 and at the other end to a lever 46 which is a socket for a detachable handle 47 and which is also pivoted to a pump plunger 48.

The innermost jack plunger 44 carries at its upper end a work engaging member 49 which is a duplicate of the member 20 of Figures 1-3 and is secured to its plunger in the same or similar manner in which that member is secured to its screw 18 (Figures 1-3). The embodiment of Figure 4 includes also a pair of arms 28 (Figures 1-3).

Operation

If a hood or fender is brought in that is deformed, the screws 18 or plungers 43, 44 are sufficiently retracted to permit the insertion of the deformed work portion between the members 20 or 49. The portion of the work extending from the apparatus is clamped in the slot 38 by screws 39. Then the screws or jack plungers are caused to move towards the work and restore the original shape.

It will therefore be apparent that I have devised a very practical and highly efficient apparatus well adapted for the carrying out of all the objects of the invention, and that while I have

illustrated two practical and satisfactory forms of embodiment of the essential features of my improvement the embodiment is susceptible of various modifications within the scope of my invention. I therefore desire to be understood as reserving the right to make all changes and modifications falling within the spirit and scope of the invention as defined by the appended claims.

Having thus described my invention, what I claim and desire to secure by Letters Patent is:

1. An apparatus of the class described comprising a pair of spaced parallel base pieces, a pair of columns each secured at its lower end by diagonal braces to one of the base pieces and having near either of two longitudinal opposite edges a series of spaced holes, two vertically spaced sets of beams bridging the space between the columns and having secured to either end a pair of apertured angle irons, bolts, each passing through an angle iron aperture and a selected hole in a column, a plurality of cross bars each countersunk in the upper and lower surface of each set of beams, a flanged bushing internally and exteriorly threaded, carried by each cross bar, a lock nut for each bushing, a jack depending from each upper cross bar of the upper set of beams through said bushing and guided by the bushing of a lower cross bar of that set, a jack rising from a flanged bushing carried by the upper cross bar of the other set and guided by a bushing in a lower cross bar of that set, each jack having a work engaging member in confronting relation to another member of the other set, and means adjustably connected to each base piece and adjustable as to length and angularity for clamping and holding the work operated on.
2. An apparatus as set forth in claim 1, where in said work engaging member includes a soft covering and means securing said covering to said member.

JOHN FRANKLIN O'KELLEY.
